EMERGENCY UNCHOKING ELEVATOR

Daniel E. Krehbiel and Elmer Zerger,
Pretty Prairie, Kans.

Application March 10, 1950, Serial No. 148,762

4 Claims. (Cl. 198—44)

1

This invention relates to elevators of the industrial type having screws or chains with buckets or flights for conveying products such as grain, coal, and the like upwardly to bins, hoppers and distributing conveyors, and in particular this invention relates to an auxiliary or emergency elevator for unchoking or relieving an elevator in a break down where products have dropped downwardly through the elevator shaft and accumulated in the boot pit, or lower end of the housing so that the elevator is inoperative until the products are removed.

The purpose of this invention is to provide means for incorporating a comparatively small emergency elevator in the boot of an industrial elevator for removing products that choke the elevator where the elevator has been halted by a break down or the like, and that may also be used for removing accumulations of products in a pit or around the lower end of an elevator.

The usual industrial type elevator is formed with chains having buckets thereon and the buckets scoop up grain, coal or the like from a hopper or boot at the base of the elevator and carry the products upwardly through the elevator shaft. In this type of elevator products are fed through chutes of feeder conveyors through the boot of the elevator and when the elevator is accidentally halted the products are continuously fed until manually stopped and in this short period of time sufficient products are deposited in the boot of the elevator to choke the same. The same is true in the elevator of the screw type. With this thought in mind this invention contemplates an auxiliary elevator either of the chain and bucket type or of the screw or auger type which is positioned to receive products from the boot of the larger elevator whereby the products are conveyed to a temporary bin in which they are stored until the elevator is repaired and from which the products may flow by gravity into the boot of the elevator after the elevator is running.

The object of this invention is, therefore, to provide means for incorporating an auxiliary elevator in the boot or hopper at the lower end of an elevator for relieving products from the elevator boot in an emergency.

Another object of the invention is to provide an auxiliary emergency elevator that may be used in combination with elevators of different types.

A further object of the invention is to provide an auxiliary emergency elevator for unchoking or relieving elevators which is of a simple and economical construction.

With these and other objects and advantages in view the invention embodies an elevator having a feeder conveyor or chute at the lower end with a discharge chute at the upper end whereby the feeder conveyor or chute at the lower end is positioned to be inserted or attached to a boot or hopper at the lower end of an elevator.

2

Other features and advantages of the invention will appear from the following description taken in connection with the drawings wherein:

Figure 1 is a side elevational view illustrating the auxiliary elevator in combination with an elevator of the grain carrying type.

Figure 2 is a longitudinal section through the auxiliary elevator taken on line 2—2 of Figure 1 and showing the elevator removed from the main elevator.

Figure 3 is a front elevational view illustrating the auxiliary elevator unit.

Figure 4 is a cross section through the auxiliary elevator taken on line 4—4 of Figure 2.

Figure 5 is a detail showing a gate in the lower end of a bin positioned to receive products from the auxiliary elevator.

Figure 6 is a section similar to that shown in Figure 2 illustrating a modification wherein the auxiliary elevator is formed with a screw or auger.

Referring now to the drawings wherein like reference characters denote corresponding parts the emergency auxiliary elevator of this invention, in the design shown in Figure 1, includes a tubular elevator shaft 10 having a boot 11 on the lower end, a housing 12 on the upper end with a chute 13 depending therefrom. The boot on the lower end is provided with a feeder tube 14 having a screw conveyor 15 therein which feeds products to the boot or hopper 11 from which they are elevated by flights 16 on an endless belt 17.

In the design shown the auxiliary elevator is of the belt type wherein spaced flights are mounted on the belt and positioned to scrape grain and the like upwardly through the tube 10. The endless belt 17 extends around a tail pulley 18 on a shaft 19 which is journaled in a bearing 20 of the boot 11 and the screw conveyor 15 is formed with a spiral vane which is positioned on the shaft 19. The outer end of the tube 14 is provided with an opening 21 through which grain and the like pass to the screw conveyor 15. The tube 14 is secured in the side of the boot 11 by a flange 22 and the tube is supported by a diagonal brace 23.

The belt 17 also extends over a head pulley 24 on a shaft 25 that is journaled in bearings 26 and 27 on the housing 12 and the shaft is provided with a pulley 28 by which the elevator is operated from a motor 29 by a belt 30, the belt 30 being positioned over a pulley 31 on the motor shaft.

With the parts arranged in this manner the tube 14 on the lower end of the auxiliary elevator is extended into a recess or hopper 32 at the lower end of a boot 33 of a main elevator in which buckets 34 are carried on an endless belt or chain 35. The elevator is provided with a pulley, or with sprockets as indicated by the numeral 36 and the pulley or sprockets are mounted on a shaft 37.

With the tube 14 extended under the main elevator products accumulating in the boot 33 pass through the opening 21 and into the screw conveyor by which the products are fed to the tube or shaft 10 where they are picked up by the flights 16 and conveyed upwardly through the tube 10 to the housing 12 from which they pass through the chute 13 into a temporary storage bin 38. The bin 38 is supported by posts 39 and a gate 40 at one side thereof holds the products therein until the main elevator is repaired.

The gate 40 is actuated by a rod 41 and, as illustrated in Figure 5 the gate is slidably mounted in tracks 42 and 43 at the sides of an opening 44. A chute 45 is provided at the lower end of the opening over which the products pass to the elevator boot 33 when the gate 40 is open.

The motor 29 is mounted on a platform 46 that is mounted on the elevator shaft or tube 10, as illustrated in Figures 1 and 3.

In the design illustrated in Figure 6 the auxiliary elevator is formed with a screw conveyor 47 in a tubular shaft 48, similar to the tube 10 and this elevator is provided with a hopper 49 that is positioned to receive products from a boot 50 of a main elevator, or the like wherein the products drop into the auxiliary elevator by gravity.

The shaft 51 of the screw conveyor 47 extends into a motor housing 52 mounted on the upper end of the tube 48 with the motor housing having a flange 53 that is bolted to a flange 54 of the tube 48 by bolts 55. A chute 56 at the upper end of the shaft 48 carries the products back to a bin similar to the bin 38 by gravity, and from the bin the products flow to the boot of the elevator casing when the elevator is repaired.

With the parts arranged in this manner the tube 14 is positioned in a hopper or recess below the lower pulley of an elevator and with the upper end positioned to deliver products into a temporary storage bin, products accumulated in the lower end of an elevator housing or boot are conveyed to the temporary storage bin, and after the elevator is repaired the products are delivered by gravity from the temporary storage bin to the lower end or boot of the elevator, from where they are elevated or conveyed to conveyors or bins for which they were originally intended.

The auxiliary elevator may also be used to elevate accumulations of grain or other products in a pit or around the lower end of an elevator. The grain or the like may be shoveled or scraped into the lower end of the auxiliary so that pits and the like may readily be cleaned thereby.

It will also be understood that the hopper 49, of the design shown in Figure 6, may be built into or formed integral with the boot or hopper at the lower end of an elevator, whereby a permanent installation is provided and this type of installation may be incorporated in original elevator housings and used with elevators of the types shown in Figure 1 or 6, or with elevators of other designs.

It will be understood that other modifications may be made in the design and arrangement of the parts without departing from the spirit of the invention.

What is claimed is:

1. In an emergency auxiliary elevator, the combination which comprises an elevator having a boot, a temporary storage bin positioned beside the elevator and having a chute for feeding products therefrom to the boot of the elevator by gravity, a gate in the said chute, a feeder conveyor extended into the boot of the elevator, an

auxiliary elevator positioned to receive products from the feeder conveyor and deliver said products to the temporary storage bin, a chute extended from the upper end of the auxiliary elevator for carrying products from the auxiliary elevator to the bin by gravity, and means mounted on the auxiliary elevator for driving the auxiliary elevator and feeder conveyor.

2. In an emergency auxiliary elevator, the combination which comprises an elevator having a boot, a temporary storage bin positioned beside the elevator and having a chute for feeding products therefrom to the boot of the elevator by gravity, a gate in the said chute, a tubular auxiliary elevator shaft, a tail pulley positioned in the lower end of the auxiliary elevator shaft, a head pulley positioned in the upper end of the auxiliary elevator shaft, an endless belt trained over the head and tail pulleys, flights mounted 20 in spaced relation on the outer surface of the endless belt, a feeder conveyor tube extended from the lower end of the auxiliary elevator shaft, a screw conveyor in said feeder tube actuated by the tail pulley of the auxiliary elevator, said 25 feeder tube extended into the boot of the elevator, a chute extended from the upper end of the auxiliary elevator shaft for delivering products conveyed by the auxiliary elevator to the temporary storage bin, a motor platform positioned on the auxiliary elevator shaft, a motor positioned on the motor platform, and means driving the endless belt of the auxiliary elevator by the motor through the head pulley of the auxiliary elevator.

3. In an emergency auxiliary elevator, the combination which comprises an elevator having a boot, a temporary storage bin positioned beside the elevator and having a chute for feeding products therefrom to the boot of the elevator by gravity, a gate in the said chute, a feeder conveyor extended into the boot of the elevator, an auxiliary elevator positioned to receive products from the feeder conveyor and deliver said products to the temporary storage bin, a chute extended from the upper end of the auxiliary elevator for carrying products from the auxiliary elevator to the bin by gravity, said auxiliary elevator having an opening in the lower end for receiving accumulations of products at the lower end of the said elevator.

4. In an emergency auxiliary elevator, the combination which comprises an elevator having a boot, a temporary storage bin positioned beside the elevator and having a chute for feeding products therefrom to the boot of the elevator by gravity, a gate in the said chute, a feeder conveyor extended into the boot of the elevator, an auxiliary elevator positioned to receive products from the feeder conveyor and deliver said products to the temporary storage bin, a chute extended from the auxiliary elevator for carrying products from the auxiliary elevator to the bin by gravity, and means for driving the auxiliary elevator and feeder conveyor.
